Des. 188,237
Patented June 21, 1960

188,237

DUST MOP HEAD

Louis A. Littleton, Davis and Trenton Aves.,
Point Pleasant, N.J.

Filed Aug. 18, 1958, Ser. No. 52,254

Term of patent 14 years

(Cl. D9—2)

Fig. 1.

Fig. 2.

Fig. 3.

Fig. 4.

Fig. 5.

Fig. 1 is a top plan view of a dust mop head showing my new design;

Fig. 2 is a side elevational view;

Fig. 3 is a front elevational view;

Fig. 4 is a rear elevational view; and

Fig. 5 is a sectional view taken along the lines 5—5 in the direction of the arrows on Fig. 1, thereof.

The fragmentary handle shown in broken lines in Figs. 1 and 2 is for illustrative purposes only.

I claim:

The ornamental design for a dust mop head, substantially as shown and described.
